DESIGN FOR A DOLL

Mary Elizabeth Granville, Philadelphia, Pa.

Application January 20, 1944, Serial No. 112,281

Term of patent 14 years

(Cl. D34—4)

To all whom it may concern:

Be it known that I, Mary Elizabeth Granville, a citizen of the United States, residing at 5335 Belfield Avenue, Philadelphia, in the county of Philadelphia and State of Pennsylvania, have invented a new, original, and ornamental Design for a Doll, of which the following is a specification, reference being had to the accompanying drawing, forming part thereof.

I claim:

The ornamental design for a doll, as shown.

MARY ELIZABETH GRANVILLE.
